UNITED STATES PATENT OFFICE

2,657,961

PISTON FOR INTERNAL-COMBUSTION ENGINES

Dietrich von Lassberg, Augsburg, Germany, assignor to Maschinenfabrik Augsburg-Nürnberg A. G., Augsburg, Germany, a corporation of Germany

Application March 15, 1950, Serial No. 149,711.

7 Claims. (Cl. 309—9)

1

This invention relates to a piston for internal combustion engines.

It is the object of the present invention to provide a piston which is heat-resistant in case of very high thermal stresses without requiring artificial cooling and in which the piston body part bearing the piston rings is kept so cool that sticking of the piston rings is safely prevented.

With this and further objects in view which will hereinafter appear, according to the present invention the piston is made entirely or partly of sintered metallic and ceramic powders, the ceramic powder having special heat insulating and heat resistant properties and a high thermal shock resistance. The whole piston or only the upper part thereof may consist of a homogeneous powder composition. According to a special feature of the invention, however, the mixing ratio is gradually changed, in such a way that the top of the piston consists of pure ceramic powder while the percentage of metal powder is gradually increased and the material consists of pure metal powder at a certain distance from the combustion chamber. Thus it is possible to weld or sinter the upper piston part consisting of this sintered mixture to a lower piston part consisting of metal without ceramic admixtures while avoiding the detrimental action of different coefficients of thermal expansion at the joint.

A piston according to the present invention ensures an efficient heat insulation without the requirement of a direct cooling.

Other and further objects, features and advantages of the invention will be pointed out hereinafter and appear in the appended claims forming part of the application.

In the accompanying drawing a now preferred embodiment of the invention is shown by way of illustration and not by way of limitation.

The drawing shows an axial section of a piston having the invention applied thereto. It will be seen that the top part of the piston 1 consists of a sintered mixture of a heat-insulating, heat-resistant powder, composed, for instance, of steatite and silicon carbide, with a metal powder, preferably iron powder. The mixture is composed in such a way that the top face of the piston consists of heat insulating powder 2 containing little or no metal powder admixtures while the portion of the piston near the joint 3 between the top part 1 and the lower part 4 of the piston consists of pure metal powder, i. e. of metal powder without ceramic admixtures. The top part 1 of the piston is connected to the lower part 4 by sintering or welding. However,

2

it is also possible to make the top part and the lower part of a single piece, whereby the joint 3 which in the first mentioned embodiment is not visible on the finished piston, will be dispensed with entirely. In this case, the lower part of the piston would also consist of sintered metal powder, without ceramic admixtures. The transition zone between the homogeneous end parts consisting solely of ceramic powder or solely of metal powder, respectively, without admixtures of the other component, may then extend over a larger zone, but the piston rings 6 should already be disposed in a part of the piston body which is substantially screened from the heat produced by the combustion above the piston, by the insulating layer consisting of thermally insulating powder 2.

While the invention has been described in detail with respect to a now preferred example and embodiment of the invention it will be understood by those skilled in the art after understanding the invention, that various changes and modifications may be made without departing from the spirit and scope of the invention and it is intended, therefore, to cover all such changes and modifications in the appended claims.

Having thus described my invention, I claim as new and desire to secure by Letters Patent:

1. A piston element for an internal combustion engine piston, comprising a layer of sintered ceramic powder forming a top working surface of the element, an intermediate zone consisting of a sintered mixture of ceramic and metal powder, with the percentage of metal powder gradually increasing towards the bottom of the element, and a bottom part consisting of sintered metal powder substantially free of ceramic admixtures for attachment to said piston.

2. A composite piston for internal combustion engines having a top working surface and comprising sintered metal powder and ceramic material admixed in varying proportions in said piston, said ceramic material forming substantially all of said top surface providing a heat resistant, thermal shock resistant, heat insulating layer on said piston, and the proportion of metal powder in said admixture gradually increasing in said piston below said top surface.

3. A composite piston for internal combustion engines having a top working surface and comprising sintered metal powder and ceramic material admixed in varying proportions in said piston, said ceramic material forming substantially all of said top surface providing a heat resistant, thermal shock resistant, heat insulating

layer on said piston, and the proportion of metal powder in said admixture gradually increasing up to 100% in portions of said piston more remote from said top surface.

4. A composite piston for internal combustion engines having a top working surface and comprising a sintered admixture of metal powder and ceramic material, said top surface being formed substantially entirely of said ceramic material and being substantially free of said metal powder providing a heat resistant, thermal shock resistant, heat insulating layer across the top of said piston and portions of said piston below said top surface being formed of continuously decreasing proportions of said ceramic material and continuously increasing proportions of said metal powder.

5. A composite piston for internal combustion engines comprising at the top thereof a heat insulating, heat resistant, thermal shock resistant layer of sintered ceramic material and a solid metal portion below said ceramic layer, said ceramic material being admixed with and gradually blending into said solid metal portion at the interface thereof.

6. A composite piston for internal combustion engines comprising a lower metal portion and a heat insulating, heat resistant, thermal shock resistant layer over the top of said lower portion, said layer comprising a sintered admixture of metal powder and ceramic material, the top sur-

face of said layer being formed substantially entirely of said ceramic material and the lower surface of said layer being formed substantially entirely of said sintered metal powder providing a fusible joining of said layer with said lower metal portion.

7. A heat insulating, heat resistant, thermal shock resistant top layer for attachment over the top working surface of a piston for an internal combustion engine comprising a sintered admixture of metal powder and ceramic material, the proportions of said metal powder and said ceramic material continuously varying throughout said layer with the top surface of said layer being formed substantially of said ceramic material and the bottom surface of said layer being formed substantially of metal providing a fusible metallic lower surface on said layer for attachment to said piston.

DIETRICH VON LASSBERG.
